UNITED STATES PATENT OFFICE.

GEORGE W. DOVER, OF PROVIDENCE, RHODE ISLAND, ASSIGNOR TO DOVERCRAFT COMPANY, INC., OF PROVIDENCE, RHODE ISLAND, A CORPORATION OF RHODE ISLAND.

CURTAIN SUPPORT.

Application filed October 22, 1927. Serial No. 228,048.

This invention relates to an improved curtain support for windows or the like and has to do more particularly with improved means for securing a curtain rod to a window casing whereby the rod may be quickly and easily placed in position on the window or removed therefrom.

One object of the present invention is to provide a device of this character wherein the curtain rod may be readily placed in position upon the window and easily removed therefrom, and at the same time the means for securing the rod to the window are such as to hold the rod firmly in position when attached and substantially prevent any sagging of the rod under the weight of the curtains.

Another object of the invention is to provide a device of this character wherein attaching means for securing the rod to a window are such as to permit the attachment of the rod to the window by a straight movement of the rod towards the window and at the same time provide an exceptionally firm holding means for the rod which will substantially prevent any movement of the rod relative to the supporting bracket.

A further object of the invention is to provide a device of this character wherein the rod is secured to the bracket by frictional means instead of by a lock or detent, thus providing a more firm support for the rod and producing a structure of greater rigidity.

Other objects and advantages of the invention relate to various improved details of construction and novel arrangements of the parts as will be more fully set forth in the brief description to follow.

Referring to the drawings:

Fig. 1 is a top plan view of the support as attached to a window casing and showing one of the two or more rods which may be employed.

Fig. 2 is a vertical sectional view, taken along the line 2—2 of Fig. 1.

Fig. 3 is a vertical sectional view, taken along the line 3—3 of Fig. 2.

Fig. 4 is a vertical sectional view, taken along the line 4—4 of Fig. 2, and

Fig. 5 is a perspective view of the bracket.

In devices of this general character as heretofore employed a lock or detent has been employed for holding the rod to the lug of the bracket, such lock or detent com-

prising an enlargement or detent portion adapted to slip into a depression or cavity whereby the end of the rod is locked upon the lug. In practice a certain amount of play results when the parts thus made are in assembled position, whereby the rod is capable of considerable movement relative to the bracket and the rod has a tendency to sag under the weight of the curtains.

It has been found that by forming the lug of such width as to extend entirely across the channel of the rod and by the employment of frictional means for holding the parts together a more rigid structure may be provided and one in which the sagging of the rod under the weight of the curtain is obviated. In the present embodiment of the invention 1 designates a portion of a window casing to which brackets 2 are secured by screws or other fastening devices 3. Each bracket 2 is provided with one or more lugs 4 formed integral therewith and tapered from the bracket towards the free end thereof, as best shown in Fig. 2. In the form of the invention as illustrated herein each bracket 2 is provided with two lugs 4 although a greater or less number may be employed dependent upon the number of rods it is desired to use. In the present case also, only one rod is shown, as the addition of a second rod would in no way enhance the clearness of the disclosure.

The rod 5 shown herein is formed of sheet metal and comprises a flat body portion 6 having inturned lateral edges 7 to form a channel 8 the width of the channel being slightly less than the width of the lug 4 at a point adjacent to the bracket but materially greater than the width of the lug adjacent to its free end. As shown herein, the rod 5 is made in one piece but may be formed of two sections, the end of one section telescoping within the end of the other, as is well known in the art. The opposite ends 9 of the rod 5 are bent inwardly at substantially right angles to the main portion of the rod and the lugs 4 slidably engage the channel 8 in the bent ends 9 of the rod. Each lug 4 is provided with a struck out portion 10, located intermediate its length, of sufficient width to frictionally engage the inturned edges 7 adjacent to the ends of the rod. Portions 12 of the inturned lateral edges 7 preferably are depressed or bent inwardly in such a manner as to engage the struck out 110

portions 10 of each lug when the ends of the rod 5 are telescoped over the lugs and forced into close engagement with the bracket. The inbent portions 12 of the inturned edges 7 5 preferably are spaced a short distance from the extreme end portions of the rod to permit the ends of the lugs to enter freely into the channel 8. As the bent end 9 of the rod 5 is forced over the lug 4, the struck out portion 10 lightly engages the inturned edges 7, and upon the lug being forced further into the channel 8 the struck out portion 10 is brought into engagement with the inbent portions 12 and the edges of the lug at its 15 wider part engage the sides of the channel 8 to press firmly thereagainst and slightly spread the rod. Thus the rod 5 is firmly held by the frictional contact of the edges of the lug with the sides of the channel as well 20 as by the frictional contact of the struck out portion 10 contacting with the inbent portions 12 of the inturned lateral edges 7.

The above construction provides an especially firm and rigid support for the rod, 25 holding the same at all times against movement relative to the window, while at the same time permitting ready removal of the rod when desired.

While the above construction embodies the 30 preferred form of my invention, the same may be modified somewhat in practice, as, for example, by omitting the inbent portions 12 when the struck out portions 10 of the lugs extend a sufficient distance from the 35 plane of the lugs to frictionally engage the lateral inturned edges 7 with sufficient force to develop adequate frictional engagement therebetween for securely holding the parts against separation, without departing from 40 the spirit and scope of my invention as defined by the appended claims.

What I claim is:

1. In a curtain support the combination 45 of a rod having a flat body portion provid-

ed with lateral inturned edges, a bracket 45 provided with a projecting lug slideable within the end of said rod and having a portion thereof struck out from the plane of the lug and frictionally engageable with the inturned edges of the rod for forcing the 50 inturned edges slightly outwardly from the main body portion of the rod and thus holding the parts against separation solely by frictional engagement of the parts.

2. In a curtain support the combination 55 of a rod having a flat body portion and lateral inturned edges forming therewith a channel, a bracket, a tapering lug extending from the bracket for insertion within the channel and having a portion thereof struck 60 out from the plane of the lug, the edges of said lug adjacent to the portion thereof of greatest width engaging the interior of the rod at the sides of the channel and the struck 65 out portion of said lug engaging the inturned lateral edges of said rod when the lug is inserted within the channel to frictionally hold the rod against separation from the lug.

3. In a curtain support, the combination 70 of a rod having a flat body portion and lateral inturned edges, portions of said inturned edges located adjacent to the end of said rod being bent inwardly towards the main body portion of the rod through a substantial portion of their longitudinal extent, 75 a bracket provided with a projecting lug slideable within the end of said rod and having a portion thereof struck out from the plane of the lug and opposed to the inwardly bent portions of the inturned edges of said rod when the parts are in assembled position to frictionally retain the rod against separation from said lug.

In testimony whereof I have affixed my 85 signature.

GEORGE W. DOVER.
